ADOLPH RYDQUIST, OF ROCHESTER, NEW YORK.

CHECK-CONTROLLED APPARATUS.

1,252,036.

Specification of Letters Patent.

Patented Jan. 1, 1918.

Application filed May 15, 1915. Serial No. 28,255.

To all whom it may concern:

Be it known that I, ADOLPH RYDQUIST, of Rochester, in the county of Monroe and State of New York, have invented certain new and useful Improvements in Check- Controlled Apparatus; and I do hereby declare the following to be a full, clear, and exact description of the same, reference being had to the accompanying drawings, forming a part of this specification, and to the reference-numerals marked thereon.

My invention relates to check controlled apparatus, and it has for its object to simplify the construction of machines of this type and to provide an arrangement of parts which will insure the perfect and complete operation of the machine under all conditions of service. A further object of the invention is to provide new and improved mechanism for receiving and discharging a proper predetermined medium capable of making operative the combined parts of the machine for the delivery of merchandise therefrom and to prevent the use of spurious mediums for accomplishing the same result. Still another object of the invention is to provide mechanism whereby if an improper medium for operating the machine is inserted therein the same will be returnable therefrom through the opening in which it was first inserted.

Another object of my invention is to provide mechanism for insuring the positive discharge of the check or controlling medium from the carrier to avoid any possibility of the medium lodging permanently in the carrier and interfering with further use of the same. With these and other objects in view the invention consists in certain novel features and forms of construction as will be hereinafter more fully described and pointed out in the specification and claims.

In the drawings:

Figure 1 is a vertical sectional view through the center of a machine embodying the features of the invention;

Fig. 2 is a rear elevation with the back of the casing removed;

Fig. 3 is a sectional elevation taken on line $a-a$ of Fig. 2;

Fig. 4 is a horizontal sectional view on line $b-b$ of Fig. 1;

Fig. 5 is a front view of a mounting and check controlling plate;

Fig. 6 is a rear view of the check con-

trolling mechanism in normal position for receiving a coin or check;

Fig. 7 is a similar view in which the check carrier has been turned to carry the check partially around;

Fig. 8 is a front view of the carrier removed showing a check inserted in the mechanism, the carrier remaining in its normal position;

Fig. 9 is a front view of the carrier after it has discharged the check and moved to the limit of its forward position, and

Fig. 10 is an enlarged detail sectional view through the check positioning mechanism.

Similar reference numerals throughout the several views indicate the same parts.

For convenience in the following description, I will employ the term "check" and "check-controlled", in reference to a medium for operating the machine, which medium may constitute a coin, disk, or any form of blank adaptable for use in a machine of this kind, it being understood that generally speaking a coin will be employed for this purpose.

Referring to the drawings by numerals, 1 designates the front, 2 the back and 3, the sides of a casing, the bottom of which contains the operating mechanism over which is superimposed the delivery mechanism as shown in Figure 1. The casing is provided with a chute 4 through which merchandise is intended to be delivered. The chute is formed by rearwardly extending plates 5 and 6, the plate 6 extending back to a stationary frame 7 and returning to the front of the casing as shown in Fig. 1. The structure shown in the upper portion of Fig. 1 is particularly adaptable for the delivery of small articles of merchandise such as chewing gum or candy in packages as shown at 8, although the invention is not intended to be limited to this class of merchandise. A transparent plate 9 to make visible the package 8 is positioned in front of an opening 10 formed in a guide plate 11 coacting with a guide plate 12 to form a delivery channel leading to the chute 4. The guide plate 12 is secured to the stationary frame 7 in any convenient manner as shown. A holding member for supporting the merchandise 8 upon the frame 7 is provided as shown in Fig. 1 and consists of a hook portion 13 engaging the frame 7 in a notch 14 formed thereon and a horizontal portion 15

80

90

95

100

105

110

15 extending partially under the merchandise to engage the same. A container 16 for receiving a plurality of the packages 8 is secured to the holding member so that the 5 container and holding member both may be removed bodily from the casing at will, to be refilled and returned to the casing whenever the occasion demands.

Extending from the front of the stationary frame member 7 are flanged projections 18 between which is formed an opening 19 through the web of the frame to permit rotation of a delivery member mounted on a shaft 20 journaled in the projections 18. The delivery member consists of a hollow cylindrical portion 21 having mounted on each end thereof carrying members 22 with openings 23 formed therein for receiving projections 24 carried by the cylindrical member. The projections are adapted to extend through the openings 23 and are hammered down on the outer face of the carrying members to hold the same rigid upon the cylindrical member. The 25 carrying members are shown rectangular in form with equal sides and at the corners of the members are provided projections 25 forming therebetween recesses 26 for receiving and holding ready for delivery the 30 packages 8 as shown in Fig. 1. One of the carrying members is provided with outwardly extending pins 27 equidistant from the center of the member and positioned in the corners of the rectangular portion 35 thereof and adapted to be engaged by an actuator 28 for the purpose of rotating the delivery member to deliver merchandise through the chute 4 in a manner which will presently be described. The actuator 28 is 40 positioned in the back and at one side of the channel like frame member and is formed of two flange members 29 and 30 positioned at right angles to each other as shown in Figs. 3 and 4. The actuator is held in sliding engagement with the frame 7 by means of depressed guides 31 formed in a flange 32 of the frame and adapted to engage the flange 30 of the actuator. The flange 29 of the actuator is guided by a rearwardly 45 extending member 33 carried by the frame which member also serves the purpose of holding the actuator in position upon the frame. The actuator is provided with a notch or cut 34 positioned at the juncture of the flanges 29 and 30 and extending into each flange a short distance to receive the pins 27 of the delivery member as the latter is rotated in the discharge of merchandise 50 from the machine. Connecting with the cut 34 in the flange 30 of the actuator is a slot 35 adapted to receive the end 36 of a lever 37 pivoted at 38 to the flange 29 of the actuator. The end 36 of the lever is normally held in the slot 35 by means of a spring 39, 60 one end of which is secured to the flange 30

of the actuator and the other end adapted to engage a projection 40 carried by the end of the lever opposite the end in the slot 35. In the bottom of the flange 29 of the actuator a series of openings 41 are formed to receive the teeth 42 of a gear sector 43 mounted on a hollow shaft receiving extension 44 projecting rearwardly from the check carrier 45. The carrier together with the extension 44 is rotatably mounted on a fixed 70 axle 46 having one end screwed into the carrier mounting plate 47 and the other end threaded and passing through a rearwardly and downwardly extending supporting member 48 on the frame 7. A nut 49 is 75 screwed on the threaded end of the axle 46 against the back of the supporting member 48 to hold the carrier in position. A handle 50 mounted on a disk 51 from which extends a shaft 52 passing through the axle 80 46 is provided as shown in Fig. 1 for operating the carrier 45 either to discharge a check or coin into the machine for securing merchandise therefrom or to return any improper medium to the operator which fails 85 to permit the carrier to be operated through its full stroke under normal conditions. In providing mechanism designed to reject improper checks or coins it is of course necessary to construct the mechanism in such a 90 way that the same will determine whether the inserted medium is of the proper and exact thickness desired as well as the actual predetermined diameter and true circular form necessary to operate the machine as 95 constructed. It will be understood that in accomplishing this result the check or coin positioning members must determine the validity of the inserted medium before the same has reached a point in the carrier from 100 whence it can not be returned, otherwise the machine would become inoperative and useless after the insertion of any check or coin not intended for use therein. In designing the mechanism necessary to embody these 105 improvements the check carrier 45 is provided with a substantially semicircular plate like member 53 to which is attached a holding plate 54 of the same general shape as the member 53. The holding plate 54 is 110 positioned immediately in the rear of the mounting plate 47 which latter is spaced from the frame 7 and supported by upper and lower post members 55 and 56 respectively and a third post member 57 shown 115 in Figs. 6 and 7. The front of the carrier is clearly shown in Figs. 8 and 9 and the rear thereof in Figs. 6 and 7. The carrier 45 is provided with a check receiving recess 58 formed in the face of the plate like portion 53 of the carrier, the plate 54 forming the outer wall of the recess as shown in Fig. 1. The recess 58 extends entirely through the carrier in order to receive a 120 check ejecting slide 59 positioned therein 125 130

with space left at the top thereof of sufficient depth to neatly accommodate a check or coin for operating the machine. A groove 60 is formed in the center of the recess in 5 the plate member 53 to receive a projection 61 carried by the check ejecting slide whereby means is provided for guiding the slide centrally of the recess. A slot 62 is formed in the center of the slide to permit of the 10 proper movement of the slide with respect to the axle 46. One side of the check ejecting slide is beveled as shown at 63 to slidably engage a beveled wall 64 forming one of the sides of the check receiving recess, 15 said beveled wall acting as a means for assisting in determining the proper thickness of a check for operating the machine as will be more fully pointed out hereinafter. The slide is provided with an arm 65 carrying 20 at the outer end thereof a projecting pin 66 adapted to be engaged by a segmental extension 67 of an operating member 68 mounted on the axle 46 between the mounting plate 47 and the holding plate 54. The operating 25 member 68 is provided with an aperture 69 adapted to receive a pin 70 carried by the disk 51 of the handle 50 so that when the handle is turned to the left the operating member will likewise turn and the segmental extension engaging the pin 66 will move 30 upwardly and lift the ejecting slide to return to the operator any improper check inserted in the machine. As a means for returning the slide to its normal position after 35 it has ejected an improper check a bifurcated projection 71 is carried by the arm 65 and is adapted to normally rest against a stop lug 72 on the carrier. A similar lug 73 is mounted on the carrier and a shaft 74 is 40 passed through the lugs and held thereon. A washer 75 is mounted on the shaft and rests against the projection 71. A spring 76 is mounted on the shaft between the lug 73 and the washer 75 so that when the check 45 ejector is moved upwardly the projection 71 compresses the spring and when the handle 50 is released the spring forces the ejector back to its normal position as shown in Figs. 6 and 7.

50 The segmental extension 67 of the operating member 68 as well as being adapted to lift the check ejecting slide is also adapted to rotate the carrier 45 by engaging the sloping edge 77 of the holding plate 54 as shown 55 in Fig. 8. This is accomplished by turning the handle 50 to the right which will move the segmental projection of the operating member to the left and turn the carrier in the direction which the handle is being 60 turned.

In providing means for determining the character of any check that may be inserted in the recess 58 of the carrier and for locking the carrier against operation when an 65 improper check is inserted the carrier plate

53 is provided with a rearwardly extending member 78 having chambers 79 and 79^a to receive a locking member 80 and a locking and positioning member 81 movable outwardly from the chamber by means of 70 springs 82 and 83 respectively through openings formed in the holding plate 54. Adjacent the member 78 is a rearwardly projecting boss 84 through which an opening is formed leading to the coin receiving recess 75 58. Extending through the opening in the boss 84 is another coin positioning member 85 provided with a right angle extension 86 adapted to pass through the locking member 80 in the chamber 79 and to normally 80 rest in a diagonally positioned transverse slot 87 through the extension 78, as shown in Figs. 6 and 7. The extension 86 of the positioning member 85 being held rigid with respect to the locking member 80 and the extension being free to slide in the slot 87, the spring 82 will serve to move the locking member 80 and the positioning member 85 simultaneously while the locking and positioning member 81 is operated separately 85 by the spring 83. A locking shoulder or abutment 88 in the mounting plate 47 is formed at the end of an inclined member 89 of the mounting plate 47 and the outer ends of the locking member 80 and locking and 90 positioning member 81 are adapted to normally rest on the inclined member 89 at the beginning of the incline and in line with the inner surface 90 of the mounting plate 47 as shown in Fig. 10 where a check 91 of 100 the proper diameter and thickness is shown inserted and positioned transversely by the positioning member 85 and laterally by a reduced portion 92 of the positioning member 81. In this figure the back edge of the check 105 91 at one side thereof is shown engaging the beveled wall 64 of the recess 58 and at the opposite edge of the check rests on the reduced portion 92 at the bottom of a tapered portion 93 integral with the reduced portion. The positioning member 85 is holding the check against the rear face of the holding plate 54 and since the check is of proper thickness the locking member 80 is held in a fixed position and out of line with 110 the abutment 88 and free to pass the inner surface 90 of the mounting plate 47. Also the reduced portion 92 is similarly held with respect to the face 90 for the reason that the tapered portion 93 has engaged the rear of 115 the check and prevented any further outward movement of the positioning member so that with the positioning and locking members held in the positions shown in Fig. 10 the carrier is free to turn to the right to 120 later discharge the check into the machine.

If the check in Fig. 10 were of a smaller diameter than shown, though of proper thickness it can readily be seen that the spring 83 would force the taper portion 93 125

65 130

against the check until the same moved over to engage the beveled wall 64, if the carrier were moved from its normal position and that in so doing the reduced end 92 would engage the abutment 88 and prevent further operation of the carrier. Likewise if the check were of proper diameter but of less thickness than shown the spring 82 would force the positioning member 85 and locking member 80, and positioning member 81 outwardly as the carrier moved forward, the ends of the locking member 80 and positioning member 81 moving on the inclined member 89 until they engaged the abutment 88 and locked the carrier against further movement. In this case the tapered portion 93 of the positioning member 81 would engage the edge of the check of less thickness and force the same over until it touched the beveled wall 64 at a point nearer the holding plate 54 than shown in Fig. 10, thus allowing the positioning member to be forced outwardly to engage the abutment as the carrier moved to the right. Also if the check shown in Fig. 10 constituted a disk having a hole through the center thereof it will readily be seen that the positioning member 85 would be free to extend through the disk and into an aperture 94 formed in the holding plate 54 thus permitting the outer end of the locking member 80 to travel on the inclined member 89 to engage the abutment 88 as the carrier moves forward. The side of the spring containing member 85 carrying the spring 82 is adapted to be opened on the end to permit of the insertion therein of the locking and positioning members 80 and 85 and the spring 82 and is closed by a plate 95 held in position by a screw 96.

It is highly important that at the end of the operation of the check carrier, means be provided for positively discharging the check from the carrier and for this purpose I provide means for moving the ejecting slide relatively to the carrier at the end of the latter's movement. This is accomplished by providing a stationary projection 97 on the mounting plate 47 and arranged in such a position as to engage the pin 66 of the ejecting slide arm 65 when the carrier has moved the proper distance. The projection 97 engaging the pin 66 serves to hold the ejecting slide against further rotative movement and as the carrier continues to the end of its turning movement the slide begins to pivotally move with respect to the projection 97 through the medium of the pin 66, thus moving the slide outwardly in the recess 58 until it reaches the position shown in Fig. 9 to force the check from the carrier.

It is possible in some instances for an improper check inserted in the recess 58 to hold the locking and positioning members in the same relationship to the abutment 88 as a

proper check or coin would do, thus allowing the carrier to rotate past the locking point. A check with a correct diameter and thickness but having a portion of its periphery cut away to form a flat edge would serve to permit of such movement and in order to avoid the possibility of the machine being successfully operated by a check of this kind, I employ a supplemental locking mechanism to coöperate with the carrier in detecting a check of the character just described after the carrier has moved a limited distance past the locking point. In the present embodiment this mechanism consists of a locking member 98 pivoted on the post 56 and controlled by a member 99 also pivotally mounted on the post and rigidly connected to the locking member by means of a suitable screw 100.

The locking member 98 is normally held in the position shown in Figs. 6 and 7 by a spring 101 wound on the post 56 between upper and lower flanges 102 of the controlling member 99, the bottom end of the spring being hooked over one side of the mounting plate 47 and the top end engaging the portion of the member 99 connecting the flanges 102. The controlling member 99 is provided with an arm 103 carrying a projection 104 extending through an opening 105 in the mounting plate 47, said opening being large enough to permit of a limited amount of movement of the projection 104 therein. Mounted on the carrier is a pin 106 projecting therefrom which is intended to lock with a shoulder 107 of the locking member 98 to prevent the successful operation of the machine with an improper check after the locking pins have passed the stationary abutment 88; a stop 108 being provided on the mounting plate 47 to retain the improper check within the carrier until the pin 106 engages the shoulder 107 of the locking member 98. In a case of this kind the locking member would remain stationary as the lower end of the check ejecting slide would not move the projection 104 to actuate the locking member for the reason that the depth or diameter of the flat sided check, plus the length of the check ejecting slide would be less, or no more than equal to the distance between the stop 108 and the projection 104, so that there would be no force acting on the projection 104 to impart motion to the locking member 98. Thus the carrier would be free to turn until the pin 106 engaged the shoulder 107 of the locking member which engagement would restrict further movement of the carrier to discharge the check. However, the carrier would be free to be thrown back to its normal position to allow the improper check to be returned to the operator in a manner previously explained.

As a means for preventing the turning of

the carrier to the left of its normal position, a shoulder 109 is provided on the locking member 98 adapted to engage the pin 106 as shown in Fig. 6.

If a check or coin of the proper type is held in the check receiving recess of the carrier when the latter has reached the position shown in Fig. 7, further movement of the carrier to discharge the check into the machine would be successful, since the diameter of such a check, plus the length of the check ejecting slide would be greater than the distance between the stop 108 and the normal position of the projection 104 in the opening 105. Therefore, with the carrier in the position as shown in Fig. 7, if the operator continues to turn the handle 50 to the right the rounded lower end of the check ejecting slide will force the projection 104 in the opening 105 away from its normal position against the pressure of the spring 101 and will move the locking member and the shoulder 107 thereon out of the path of the pin 106 to allow the carrier to continue in its forward movement until the coin is discharged into the machine, the pin 66 of the arm 65 engaging the projection 97 by the time the check in the carrier has passed the stop 108, thereby moving the slide with respect to the carrier to positively eject the check from the carrier into the machine, such movement continuing until the ejecting slide reaches the position shown in Fig. 9. With the slide in this position the spring 76 will have been compressed considerably by the movement of the projection 71 on the slide and as soon as the check has been ejected the spring will return the slide to its normal position with respect to the carrier.

In order to insure a complete movement of the carrier after the pin 106 thereon has passed the shoulder 107 of the locking member 98, I provide a series of notches 110 on a portion of the periphery of the carrier and coöperating therewith is a reversible pawl 111 movably mounted on the post 55 and controlled by a spring 112 having one end positioned through a projection 113 on the pawl and the other end fastened to the frame 7 in the manner shown in Fig. 3.

As a means for partially supporting and bracing the frame 7 and parts mounted thereon, I provide a supporting rod 114 secured to the sides 3 of the casing and adapted to engage the projecting flanges 18 of the frame 7 within notches 115, as shown in Fig. 1.

In order to insure the return of the carrier 45, the actuator 28 and the parts mounted thereon to their normal position after the machine has been operated, a spring 116 is provided having one end secured to a stationary projection 117 at the bottom of the frame 7 and the other end secured to a pro-

jection 118 at the top of the flange 29 of the actuator, so that when the actuator is elevated by turning the handle 50, tension will be imparted to the spring to pull the actuator down as soon as the handle is released, thereby rotating the carrier backwardly through the medium of the teeth of the gear segment mounted on the carrier and the openings 41 in the actuator for receiving the teeth as shown in Fig. 3.

I claim as my invention:

1. In a check controlled apparatus, the combination with a check carrier having a recess to receive a check, of an actuator operatively connected to the carrier, a locking abutment, and a check controlled positioning and locking member consisting of a spring actuated pin projecting through said recess of the carrier and operating when a proper coin is not inserted so as to engage the abutment after a limited movement of the carrier.

2. In a check controlled apparatus, the combination with a check carrier having a recess to receive a check, of an actuator operatively connected to the carrier, a locking abutment, and a check controlled positioning and locking member comprising a spring actuated locking pin having mounted thereon a positioning pin adapted to be projected through said recess and adapted to move simultaneously with said locking pin, said positioning pin operating when a proper coin is not inserted in said recess to permit said locking pin to engage said abutment after a limited movement of the carrier.

3. In a check controlled apparatus, the combination with a check carrier having a recess to receive a check, of an actuator operatively connected to the carrier, a locking abutment, and a check controlled positioning and locking member projecting through said recess and operating when a proper coin is not inserted to engage the abutment after a limited movement of the carrier.

4. In a check controlled apparatus, the combination with a check carrier having a recess to receive a check, of an actuator operatively connected to the carrier, a locking abutment, and a spring actuated check controlled positioning and locking member comprising two rigidly connected parallel shafts, one of which is disposed near the center of said recess and the other outside thereof and operating when a proper coin is not inserted to engage the abutment after a limited movement of the carrier.

5. In a check controlled apparatus, the combination with a check carrier having a recess to receive a check, of an actuator operatively connected to the carrier, a locking abutment, a pair of independent check controlled spring actuated positioning members movable within said recess, and a locking

- member carried by one of said positioning members and moving in parallelism therewith whereby, when a proper coin is not inserted said locking member will engage said abutment after a limited movement of the carrier.
6. In a check controlled apparatus, the combination with a check carrier having a recess to receive a check, of an actuator operatively connected to the carrier, a locking abutment, and a pair of spring actuated positioning members movable within said recess upon movement of the carrier, whereby when a proper coin is not inserted one of said positioning members will project through said recess into engagement with said abutment after a limited movement of the carrier.
7. In a check controlled apparatus, the combination with a check carrier having a recess to receive a check, of an actuator operatively connected to the carrier, a locking abutment, and a locking member movably mounted on the carrier and provided with a tapered shoulder projecting through said recess at one edge thereof and adapted to engage the edge of a check, said shoulder operating when a proper check is not inserted to position the latter in the recess so as to permit the locking member to move into engagement with the abutment after a limited movement of the carrier.
8. In a check controlled apparatus, the combination with an oscillatory check carrier having a recess therein to receive a check, of an actuator operatively connected with the carrier, a check ejecting slide movable on the carrier within said recess to eject a check, operating means movable in one direction to actuate the slide independently of the carrier and in the opposite direction to operate the carrier, a stop arranged to engage the slide during the movement of the carrier to effect movement of the slide within said recess, a plurality of notches on the periphery of the carrier, and a reversible pawl coacting therewith to insure a complete movement of the carrier during the discharge of the check therefrom.
9. In a check controlled apparatus, the combination with an oscillatory check carrier having a recess therein to receive a check, of an actuator operatively connected with the carrier, a projection on the carrier, a movable locking device pivotally mounted in the path of the projection, a check ejecting slide movable on the carrier within said recess to eject a check, and a stationary portion disposed adjacent the periphery of the carrier and adapted to engage the check during the movement of the carrier so as to hold the ejecting slide in releasing engagement with the locking device.
10. In a check controlled apparatus, the combination with a movable check carrier having a recess therein to receive a check, of an actuator operatively connected with the carrier, a projection on the carrier, a spring controlled movable locking device mounted in the path of the projection, a check ejecting slide movable on the carrier within said recess to eject a check, and a stationary portion disposed adjacent the periphery of the carrier and adapted to engage the check during the movement of the carrier so as to hold the ejecting slide in releasing engagement with the locking member.
11. In a check controlled apparatus, the combination with a movable check carrier having a recess therein to receive a check, of an actuator operatively connected with the carrier, a projection on the carrier, a movable locking device mounted in the path of the projection, a check ejecting slide movable on the carrier within said recess to eject a check, means adapted to engage the check during the movement of the carrier so as to hold the ejecting slide in releasing engagement with the locking member and a stop carried by the movable locking device and adapted to engage said projection to limit the return movement of the carrier after ejecting the check.
